Primary Examiner — Stacia Cadmus(74) *Attorney, Agent, or Firm* — Womble Carlyle Sandridge & Rice LLP(57) **CLAIM**

The ornamental design for a wheel center cap, as shown and described.

DESCRIPTION

FIG. 1 is a perspective view of a wheel center cap, showing our new design.

FIG. 2 is a front view of the wheel center cap of FIG. 1.

FIG. 3 is a right side view of the wheel center cap of FIG. 1.

FIG. 4 is a back view of the wheel center cap of FIG. 1.

FIG. 5 is a top view of the wheel center cap of FIG. 1.

FIG. 6 is a bottom view of the wheel center cap of FIG. 1; and, FIG. 7 is a reduced perspective view of the wheel center cap, shown in its position of use.

The broken line showing of the logo and the automobile wheel is included for the purpose of illustrating environment and forms no part of the claimed design.
